UNITED STATES PATENT OFFICE.

ALBERT P. FEY, EDWIN J. FEY, AND ALBERT J. MOLTZ, OF BOONVILLE, NEW YORK.

SNOWPLOW.

Application filed July 27, 1925. Serial No. 46,410.

Our invention relates to snow plows and has for its object the provision of an apparatus which may be coupled to the front end of a tractor or other motor impelled vehicle and operated from the said vehicle to create a suction or air blast whereby snow taken up from a road will be deposited at one side of the path made by the machine. A further object of the invention is to provide simple and easily operated means whereby snow may be scraped from a road, then reduced to a fine condition free of lumps, and then blown to a point at the side of the path. The invention also seeks to provide a device which may be produced at a low cost, which will be efficient in operation and which will be strong and durable. The invention is illustrated in the accompanying drawings and consists in certain novel features which will be particularly pointed out in the appended claims.

In the drawings:

Figure 1 is a side elevation of our improved snow plow;

Fig. 2 is a plan view of the same;

Fig. 3 is a front elevation, and

Fig. 4 is a transverse section on the line 4—4 of Fig. 2.

Our snow plow includes sills or beams 1 which are adapted to be secured to the frame of a tractor, indicated at 2, and which may be of any well-known type. The sills are secured to the tractor frame so as to project forwardly therefrom, as clearly shown in the drawings, and upon the said sills we erect a frame 3 which is preferably formed from angle bars and may be of any detailed design possessing the requisite strength. Secured upon and projecting forwardly from the sills 1 and the frame 3 is a scoop consisting of a downwardly and forwardly inclined bottom plate 4 adapted to run upon the ground and scrape therefrom the snow to be removed. This bottom plate 4 has its side edges in divergent relation so that the front of the plate is wider than its rear edge and at the side edges of the said plate are rigidly secured side plates 5 which form component parts of the scoop and serve to retain the snow upon the bottom plate and direct it into the beater or breaker as the plow progresses. Rigidly supported at the rear of the side plates 5 is a hood 6 which fits over a beater or breaker consisting of a hub 7 and arms 8 rigidly secured to and radiating from the hub and disposed transversely of the machine so that, as the snow is taken up and caused to move relatively rearwardly in the travel of the machine, it will be brought against the 60 rotating beater or breaker so that the large lumps will be disintegrated and the snow passed rearwardly in such condition that it may be effectually acted upon by the discharging fan. The hub 7 of the beater is 65 secured upon a longitudinally extending shaft 9 mounted in suitable bearings upon the hood 6 and the supporting frame and equipped at its rear end with a pulley 10 about which is trained a belt 11 whereby the 70 said pulley 10 is operatively connected with a pulley 12 secured upon the engine shaft of the tractor to be actuated thereby. Within the upstanding frame 3 and secured rigidly thereto is a housing 13 having an opening 75 in its front side concentric with the beater. Arranged within this housing 13 is a fan consisting of a hub 14 secured upon the shaft 10 and arms 15 secured upon the hub 14 tangential thereto and carrying blades 80 16 at their outer ends. Upon reference to Fig. 4 more particularly, it will be noted that the hub 14 is angular in cross section and has flat sides, the arms 15 being secured to the flat sides of the hub. The arms are 85 arranged in pairs and the blades 16 are secured to and connect the outer ends of the arms in each pair. Between the arms is a disk or circular plate 17 to which the blades 16 are also secured, as indicated at 18, the 90 strength of the structure being thereby increased and the snow being more effectually broken up and discharged. It will be noted that the diameter of the central bracing disk 17 is less than the diameter of the housing 95 so that the blades 16 are disposed between the edge of the disk and the side of the housing, the snow being consequently drawn into the housing below the edge of the disk and positively engaged by the blades to be 100 forcibly driven from the housing. Rising tangentially from one side of the housing is a spout 19 which may be carried to any desired height and is equipped at its upper end with a laterally extending hood 20.

In operation, the machine is driven forward over the line of the path to be cleared by the operation of the tractor in the usual manner. As the machine progresses, the scoop 4 will take up the snow and the fan and the beater will be positively rotated at a high speed under the power of the tractor

engine. The rotation of the fan will create a suction through the housing 13 and the discharge spout 19 which will very materially aid in effecting the rearward passage of the snow which will be drawn into the range of the beater so that it will be broken up by the action of the same. From the beater the snow will be drawn directly into the housing 13 and will be positively engaged by the fan so that it will be driven into and through the spout 19, the physical impact of the fan blades cooperating with the suction of the fan to effect positive and rapid discharge of the snow.

15 The scoop is not rigidly supported but is pivoted, as indicated at 21, to the front ends of the sills 1 and upon the upper front corner of the frame 3 is mounted a rock shaft 22 having crank arms 23 fixed to and upstanding therefrom. Links 24 are pivoted to the said crank arms and to the sides 5 of the scoop and to one of the crank arms is pivoted a rearwardly extending connecting rod 25 which passes to and is pivoted 20 to a hand lever 26 fulcrumed in any convenient manner upon the tractor frame. This hand lever is equipped with a well-known latch mechanism 27 cooperating with a holding bar 28 secured upon the tractor 25 so that by properly manipulating the hand lever the scoop may be set to run at a higher or lower point or may be raised to an inoperative position at will.

30 From the foregoing description, taken in connection with the accompanying drawings, it will be seen that we have provided a very simple, compact and efficient apparatus whereby a path may be easily and rapidly formed after a heavy fall of snow.

40 Having thus described the invention, we claim:

1. A snow plow comprising a scoop, a beater arranged at the rear end of the scoop, a housing in rear of the beater having a tangential discharge spout, a fan within the housing concentric with the beater

and comprising a hub having flat sides, arms secured to the flat sides of the hub tangential to the axis of the hub, blades secured to the outer ends of said arms, the arms being arranged in pairs and the blades connecting the arms of each pair, and a reinforcing disk arranged between the arms and secured to the hub and to the inner edges of the blades.

2. A snow plow comprising a frame to be secured to the frame of a tractor, a scoop pivotally supported on the front end of said frame, a rock shaft mounted on the front of the frame at the top thereof, crank arms on the rock shaft, links connecting the crank arms with the scoop, a hand lever to be mounted on the tractor, a connecting rod connecting the hand lever with one of said cranks, a beater mounted at the rear end of the scoop, a fan in rear of the beater, a shaft common to the beater and the fan, and means for operatively connecting said shaft with the power shaft of the tractor.

3. A snow plow comprising sills to be secured to the frame of a tractor, an upright frame carried by the sills near their front ends, a scoop pivoted to the front ends of the sills, a beater at the rear of the scoop, a hood supported from the front of the upright frame and extending over the beater, a housing secured in the upright frame and rising therefrom and having a lateral discharge, a fan in said housing in axial alignment with the beater, means for connecting the fan and the beater with the shaft of the tractor, a rock shaft on the upright frame, cranks on said shaft, links connecting the cranks with the sides of the scoop, and a hand lever to be secured on the tractor and operatively connected with one crank on the rock shaft.

In testimony whereof we affix our signatures.
